UNITED STATES PATENT OFFICE.

DANIEL I. CALHOUN, OF CHICAGO, ILLINOIS, ASSIGNOR TO THE CALHOUN EXCAVATOR COMPANY, OF SAME PLACE.

COMBINED EXCAVATING AND BACK-FILLING APPARATUS FOR SEWERS, &c.

SPECIFICATION forming part of Letters Patent No. 597,312, dated January 11, 1898.

Application filed January 8, 1897. Serial No. 618,553. (No model.)

To all whom it may concern:

Be it known that I, DANIEL I. CALHOUN, a citizen of the United States of America, residing at Chicago, in the county of Cook and State of Illinois, have invented new and useful Improvements in a Combined Excavating and Back-Filling Apparatus for Sewers and the Like, of which the following is a specification.

10 My invention relates to certain new and improved apparatus the object of which is to excavate a trench, such as is made in the construction of a sewer, and at the same time to back-fill or cover the completed sewer, the dirt being taken up from the trench in advance of the sewer construction, carried therefrom, and deposited at a distance upon the completed sewer, so that it is handled but once, the ground in advance of the apparatus 20 being untouched, and the sewer in the rear of the same being fully completed and back-filled.

The invention consists in certain novel features of an apparatus which will be fully described below, and the essential portions of which will be pointed out in the claims appended hereto.

The drawings present five views of the preferred form of my apparatus, Figure 1 being 30 a side elevation of the apparatus complete, showing the manner of using the same in sewer construction. Fig. 2 is a plan view of the same. Fig. 3 is a section in the plane 33 of Fig. 2, but showing the device upon a larger scale. Fig. 4 is a detail section in plane 44 of Fig. 3; and Fig. 5 is a similar section, partly broken away, in plane 55 of Fig. 2.

Looking first at Figs. 1 and 2, M represents the advanced portion of a trench, and N the customary piling used to sustain the side walls of the trench and prevent the falling in of the dirt during the building of the brick-work of the sewer. O is a portion of said brick-work.

45 P is the earth from the excavation piled up upon the completed sewer.

A temporary track T is laid along each side of the excavation to support and render easy the moving of the excavating apparatus. A 50 hoisting-car A is run upon this track immediately in advance of the excavation, said hoist-

ing-car being provided with a suitable engine or motor a' and a tower a². Above the portion of the trench in which the construction of the sewer is going on and just in advance of the 55 back-fill P is a dumping-car B, upon which is mounted a rearwardly-inclined tower b, extending back over the fill and sufficiently elevated at its end to clear any possible elevation of dirt upon the sewer. This tower is 60 made up of two side frames b² b³, the upper portions of which are entirely separate, except at the extreme top, to allow the passage of the load between them. Both the dumping-car and the hoisting-car are mounted 65 upon wheels b' a³, so that they may be easily moved forward upon the track T as the work progresses.

Between the hoisting-car and the dumping-car is an open framework F, mounted upon 70 wheels f of sufficient length to span the portion of the trench in which the sewer construction is going on, said open frame being constructed with a minimum number of cross braces or trusses in order that it may not interfere with such construction and being yet of sufficient strength and rigidity to prevent the hoisting-car and dumping-car from being brought together under the strain of the conveying apparatus. Secured to the top of the 80 inclined tower B on the dumping-car is a carrying-cable C. Said cable extends therefrom to the top of the tower a², upon the hoisting-car, from which it passes onward over a strut c, down to the framework of the car, and is 85 fastened thereto at c'. This cable is designed to carry the load of dirt, and for such purpose is provided with a carrier c², from which is suspended a scoop E by means of a cable e, running to a drum e'. The carrier is moved 90 back and forth upon the cable C by means of an endless cable D D', running over a pulley d at the top of the inclined tower b, pulleys d' d² upon the tower a², and around a drum d³. The dirt in the trench is scooped up in 95 the scoop E in advance of the sewer construction, lifted up to the carrier c², carried across over the advancing brickwork to the inclined tower b, and there dumped upon the completed sewer by means of a tripping device 100 C'. In this operation the great strain of the carrying-cable upon the two cars is sustained

by the open framework F, the same being mounted upon the track in a manner similar to the two cars and moved forward with them step by step as the construction advances.

5 I claim as new and desire to secure by Letters Patent—

1. The combination in a sewer-excavating and back-filling device and with a suitable track adapted to span the sewer, of the hoisting-car, A, the dumping-car, B, and the intervening open framework, F, all mounted upon wheels on the track, the tower, a^2 , and the hoisting apparatus, a' , on the hoisting-car, the inclined tower, b , upon the car, B, said tower being composed of the two side portions, b^2 , b^3 , the upper portions of which are entirely separate except at the extreme top, a carrying-cable stretched between the tops of the two towers, a carrying device upon the cable, a digging and dumping device connected therewith and suitable cables and operating devices therefor to load, transport and dump the dirt; substantially as described.

2. The combination in a sewer-excavating

and back-filling device and with a suitable track adapted to span the sewer, of the hoisting-car, A, the dumping-car, B, and the intervening open framework, F, all mounted upon wheels on the track, the tower, a^2 , and the hoisting apparatus, a' , on the hoisting-car, the inclined tower, b , upon the car, B, said tower being composed of the two side portions, b^2 , b^3 , the upper portions of which are entirely separate except at the extreme top, a carrying-cable stretched between the tops of the two towers, a carrying device upon the cable, a digging and dumping device connected therewith and suitable cables and operating devices therefor to load, transport and dump the dirt; substantially as described.

In witness whereof I have hereunto set my hand, at Chicago, in the county of Cook and State of Illinois, this 31st day of December, 1896.

DANIEL I. CALHOUN.
